UNITED STATES PATENT OFFICE.

SAMUEL L. HANCOCK AND JOHN J. ORTNER, OF OAKLAND, CALIFORNIA.

SWITCH-BOX STAY.

1,246,741.

Specification of Letters Patent.

Patented Nov. 13, 1917.

Application filed September 27, 1916. Serial No. 122,403.

To all whom it may concern:

Be it known that we, SAMUEL L. HANCOCK and JOHN J. ORTNER, citizens of the United States, and residents of the city of 5 Oakland, county of Alameda, State of California, have invented an Improvement in Switch-Box Stays; and we do hereby declare the following to be a full, clear, and exact description of our invention, such as 10 will enable others skilled in the art to which it appertains, to make and use the same.

Our invention relates to a stay for switch-boxes, an attachment used for installing and fastening a switch-box in place, and it consists 15 in its novel arrangement and construction as hereinafter described.

The object of our invention is to provide a simple, compact and effective stay, cheap to manufacture and quickly and easily installed; thus effecting a gain in time, labor, and manufacturing cost.

Switch-boxes as a rule are installed in buildings between the studding before the walls are plastered and are then obscured 25 from view by the plaster. Heretofore, by means of stays attached to their sides, such switch-boxes have been fastened to the laths running parallel with their two sides. It has then been necessary to add a backing at 30 the ends of the switch-box for its further support and also to serve as a backing for the ends of the laths abutting the ends of the switch-box. The use of our improved stays makes this additional support and backing unnecessary, as our stays are fastened 35 to the ends of the switch-box adequately support the same, and also serve as a backing for the laths. We thereby effect a great gain in time, labor, and efficiency.

40 In order that our invention may be clearly understood and readily carried into effect, the same is described with reference to the accompanying drawings, in which similar numbers indicate like parts.

45 Figure 1 is an end elevation of our stay.

Fig. 2 is an isometric view of the same.

Fig. 3 is a plan view partially broken away to show the short side of our stay.

50 Fig. 4 is a perspective view showing our stays in place, with a portion of the laths broken away to better disclose the same.

In detail, our stays consist of a thin flat piece of suitable material whose central portion 55 constitutes a back, 2, of the same length and contour as the ends, 3, of the

switch-box, 4. Extensions of the said back are turned down at right angles to form ears, 5, each of which is provided with a notch, 6, adapted to receive a screw 7. Integral therewith and rising from said back 60 at right angles are two parallel sides of different lengths, 8 and 9,—the shorter side, 8, corresponding in length to the length of the back. The longer side, 9, is provided at each end with an aperture, 10, adapted to receive 65 a nail or screw. When in place the back and sides of each stay form a pocket, 11, opening outward and adapted to receive and support the ends of the laths, 12.

Our device is used as follows: A stay, its 70 longer side, 9, face up, is placed at each end of the switch-box and fastened thereto by tightening the screws, 7, which are threaded into the switch-box and received by the notches, 6. The switch-box is then attached 75 to the laths, 13, the longer sides, 9, of the stays being at right angles to the said laths, and the pockets, 11, opening outward. The laths, 12, entering the pockets, 11, further fasten and support the switch-box in position.

Having thus described our invention, what we desire to claim and to secure by Letters Patent, is:—

1. A switch-box stay consisting of an integral piece of suitable material comprising a back provided at each end with a turned-down notched-extension, and two parallel sides of different lengths rising from said back; said back and sides forming a pocket. 85

2. In a stay for a switch-box, a back provided at each end with a turned-down notched-extension, and two parallel pocket-forming sides of different lengths rising from said back and integral therewith. 90

3. A switch-box stay comprising a back provided at each end with a right-angle downward extension, notches for each extension, and two parallel pocket-forming sides of different lengths rising from said back and integral therewith. 95

In testimony whereof we have hereunto affixed our respective signatures in the presence of two subscribing witnesses.

SAMUEL L. HANCOCK.
JOHN J. ORTNER.
